UNITED STATES PATENT OFFICE.

FREDERICK W. SCHWENCK, OF CINCINNATI, OHIO.

DESIGN FOR A DECANTER.

Application filed March 19, 1923. Serial No. 5,508. Term of patent 7 years.

To all whom it may concern:

Be it known that I, FREDERICK W. SCHWENCK, a citizen of the United States of America, and a resident of Cincinnati, in the county of Hamilton and State of Ohio, have invented a new, original, and ornamental Design for a Decanter, of which the following is a specification, reference being had to the accompanying drawing, forming part thereof.

Fig. 1 is a side elevation of a decanter, showing my new design.

Fig. 2 is an end elevation of a decanter, showing my new design.

Fig. 3 is an inverted plan view of a decanter, showing my new design.

I claim:

The ornamental design for a decanter as shown.

FREDERICK W. SCHWENCK.
